(57) **CLAIM**

The ornamental design for an icon for a portion of a display screen, as shown and described.

DESCRIPTION

FIG. 1 is a front view of a first embodiment of an icon for a portion of a display screen showing our new design; and, FIG. 2 is a front view of a second embodiment of an icon for a portion of a display screen.

The broken line showing of the display screens is for illustrative purposes only and forms no part of the claimed design.
